UNITED STATES PATENT OFFICE.

BERT C. MAXWELL, OF CANTON, OHIO, ASSIGNOR TO JULIUS WHITING, JR., TRUSTEE,
OF CANTON, OHIO.

MANIFOLDING-BOOK.

1,105,571.

Specification of Letters Patent.

Patented July 28, 1914.

Application filed January 16, 1908. Serial No. 411,156.

To all whom it may concern:

Be it known that I, BERT C. MAXWELL, a citizen of the United States, residing at Canton, in the county of Stark and State of Ohio, have invented certain new and useful Improvements in Manifolding-Books, of which the following is a specification, reference being had therein to the accompanying drawings.

10 This invention relates to improvements in manifolding books.

It pertains, generally, to manifold sales and order books; particularly, to that class of order books employed for keeping a continuous record of the transactions between a merchant and a customer. In such use, one of these books is issued to the customer, either to be retained by him and brought to the merchant each time a transaction is consummated, or to be kept by the merchant for the same purpose.

One of the principal objects of my invention is to provide a manifold book or pad so constructed as to be readily adaptable for various methods of use, merely by employing various styles of covers, and by arranging and operating the manifolding sheet or sheets in various ways, according to the needs of the merchant or customer.

30 Other objects of my invention will be clearly apparent from the embodiments of it herein shown and described for the purposes of illustration.

Figure 1 is a perspective view of a book embodying my improvements, closed. Fig. 2 is a perspective view of the same book, partially open. Fig. 3 is a perspective view of the same book, illustrating the method of using the book for recording a transaction.

40 Fig. 4 is a perspective view illustrating a modified style of combined cover and separator. Fig. 5 is a perspective view of a pad embodying my invention arranged in a holder which I have devised for it. Fig. 6 is a perspective view of a holder for the pad. Fig. 7 is a longitudinal sectional view of the holder illustrating the manner of inserting and withdrawing a book. Fig. 8 is a

transverse sectional view of the manifolding book. Fig. 9 is a side elevation of two sets of leaves, enlarged.

In the drawings, 2 indicates a suitable base or back. Upon it are arranged and to it are suitably attached a plurality of superposed sets of original and duplicate slips. 55 Each set of slips is preferably formed from a single sheet of paper folded intermediate of its ends at 3, to make from the upper section an original slip 4, somewhat shorter than the duplicate slip 4', which has the fold 60 at its lower end. The free ends of the duplicate slips extend beyond the free ends of the original slips, and may be suitably attached to the back so as to hold the said sets of slips in pad form. For the purpose 65 of thus holding the sets of slips together and in position on the back 2, I have devised a staple 5 having oppositely inclined, upwardly and outwardly extending prongs or limbs 5', 5", which pierce the said back and 70 the free ends of the duplicate slips of which the book is composed. As these prongs or arms 5', 5", of the staple diverge from each other, the sets of slips one after the other may be removed from the top of the pad 75 without the possibility or likelihood of the slips beneath them creeping up on the arms of the staple, or becoming loose on the back.

The upper folded-over section of each folded sheet from which an original slip 4 80 is formed, is perforated or weakened along a transverse line 6 parallel to the line of fold of the sheet. As the original slip 4 of each set of slips is detached along the line 6 from the rest of the sheet for the set, the folded-over portion of the sheet between said line of perforations and the transverse line of fold, designated by 4", may be considered a part of the duplicate slip.

7 is a manifold or transfer sheet, preferably suitably attached along the left-hand edge of the book 2, and arranged to fold over between the original and duplicate slips of each set of slips in use. The lower end of this transfer sheet preferably lies above or 95 immediately adjacent to the transverse line

of perforation 6 of each set of slips. The upper right hand corner of the manifolding or transfer sheet is suitably cut away, as indicated at 7', to expose the upper right hand corner of the free ends of the slips 4 which lie beneath.

8 is a cover suitably attached to the back and arranged to be folded over upon the pad of slips from the upper bound end thereof.

10 Preferably this cover only extends downward to or immediately adjacent to the transverse lines of perforation 6 on the sets of slips, so as to leave exposed beneath the lower end of said cover, the turned-up and 15 over portions 4^a of the used duplicate slips.

9 is a cover preferably arranged to fold over on to the pad from its end opposite to that to which the cover 8 is attached. The cover 9 has an aperture 10 through it arranged to expose a portion of the turned-over section 4^a of the used duplicate slip next beneath the said cover. The material of which the cover 9 is composed may be carried upward from the back 2, as indicated 25 at 9', then bent downward and forward, as indicated at 9^a, and then back upon itself, as shown at 9^b, to form a downward forwardly extending name-display section, adaptable for the purpose of carrying the 30 name of the customer to whom the book is assigned. This downward, forwardly-inclined name-displaying section may, however, be otherwise formed, if desired. Its purpose is to facilitate the display of the 35 customer's name in the file, holder, or place in which the book may be kept by the merchant.

40 In operation, the book, face up, is preferably grasped in the left hand. The operator looks through the opening 10 in the cover 9 and makes a mental note of the figures appearing therethrough. The cover 9 is then thrown back and the operator grasps the upturned ends 4^a of the used duplicate slips 4' and throws the said slips back, they carrying with them the cover 8, as shown in 45 Fig. 3. He then removes from beneath the carbon sheet 7, the uppermost unused original slip 4, and drops the said slip back upon the transfer sheet. Next, the balance due 50 and carried forward, as indicated at b on the turned over portion of the last used duplicate slip, is entered upon the original slip, and then the current transaction; after 55 which the sum-total of the account is struck and may be entered at a on the original slip, from where it will be transferred to the duplicate, and the sum-total to be carried forward is also written on the turned-over portion of the duplicate slip at b. The set of slips thus used is then drawn out above the transfer sheet, and the original slip 4 thereof is detached. The cover 8 and used dupli-

cate slips are dropped back upon the just used duplicate slip, and the cover 9 is then 65 thrown over on the pad. The turned-over portion of the last used duplicate slip 4' folds over and incloses the turned-over portions of the earlier used duplicate slips, so that the balance due on the account, indicated at b on said last used duplicate slip, 70 appears through the opening 10 in the cover 9, and will also appear immediately upon the throwing back of the cover 9. When desired, either or both of the covers 8 and 75 9 may be dispensed with, and the transfer medium may be employed in any other well known way.

In Fig. 4 I have shown a book in which the cover 9 has been dispensed with and the 80 cover 8 is extended beyond the line of perforations 6 and beyond the ends of the duplicate slips and provided with an under-turned end 8' which is adapted to be folded under the used duplicate slips. 85

8^a is an aperture through the said cover arranged to expose to view the section b of the turned-over section 4^a of the last used duplicate slip. Where the cover 8 is formed as just described, it serves both as a cover 90 and as a separator for the used from the unused slips.

95 It will be understood that a book constructed in accordance with my invention is readily adaptable for different uses, and that the manifolding or transfer sheets may be applied and operated in different ways without departing from the spirit of my invention.

When desired, a book embodying my invention may be used in soliciting orders 100 from different customers, the sets of slips being easily detachable from the pad intact, without loosening or in anywise disturbing the sets of slips left remaining in the pad.

105 In many instances I have found it advisable to provide a holder for a book or pad. In Figs. 5, 6 and 7, such a device is illustrated, and indicated by 11. It is preferably made of sheet metal and has a base 12, and upturned sides 13, 14. The left side 13 is 110 preferably of the same height from end to end of the holder, while the right side of the holder is cut away, as indicated at 14', to facilitate the easy operation of the sets of slips of a manifolding pad. At the lower 115 end of the holder the metal is preferably bent upwardly, as indicated at 15, and apertured at 15' to expose a name plate or card, which may, if preferred, be carried by the book or pad. The upper end of the base 12 120 of the holder is transversely depressed, as indicated at 16, preferably in curvilinear form, and the metal above this depression is bent upward at 17 and over at 17' to engage the upper end of the book or pad to be held. 125

18 is a recess adapted to expose a portion

of the upper end of a book and to facilitate its insertion into and withdrawal from the holder.

19 is a rod or wire extending transversely

5 across the holder at its upper end over the transverse depression 16, and suitably held in position in any desired manner.

In order to insert a book or pad in the holder, the cover or over-turn at the bound 10 edge of the book is directed over the rod 19, as indicated in Fig. 7, and the pad or book is then swung around into position in the holder, the depression 16 permitting this. To withdraw a book from the holder the re- 15 verse operation is followed.

The sides of the holder may be scored, as indicated at 20, and the tongues 20' of the scored portions, turned inwardly to engage the bottom or back 2 of the book and firmly 20 hold the book or pad in position in the holder.

To those skilled in the art of making devices of the class described, many alterations 25 in construction and widely differing embodiments and applications of my invention will suggest themselves without departing from the spirit and scope thereof.

I claim—

1. In a manifolding book, the combination 30 of a plurality of sets of original and duplicate slips, each set formed from a single sheet of paper folded transversely nearer to one of its ends than to the other and perforated along a line parallel to said line of fold and adjacent thereto, to form an original slip and a duplicate slip, the line of fold being substantially unweakened whereby one of said slips has a short inseparable folded-over section between the said 35 line of fold and the said line of perforations, the said folded-over end of one slip of each set being arranged to fold over and inclose the folded-over end of the prior-used slip, means for binding the ends of the longer 40 slips of said sets opposite to the ends connected with the shorter slips together, and a transfer sheet arranged to be interposed between the slips of each set of slips.

2. In a manifolding book, the combination 50 of a plurality of sets of original and duplicate slips, each set formed from a single sheet of paper transversely folded nearer to one of its ends than to the other along a substantially unweakened line and 55 perforated along a line parallel to said line of fold and adjacent thereto to form a relatively short original slip, and a duplicate slip having a short inseparable folded-over section between the said line of fold and the said line of perforations, arranged to 60 fold over and inclose the folded-over section of the prior-used duplicate slip, means for holding the ends of the duplicate slips

opposite to the ends carrying the folded-over sections in pad form, and a transfer 65 sheet arranged to lie between the original and duplicate slips of the set of slips.

3. In a book, the combination of a plurality of sets of slips, each set formed from a single sheet of paper folded transversely 70 intermediate of its ends along a substantially unweakened line and weakened along a line parallel to and adjacent to said line of fold, so as to provide an inseparable folded-over end at one end of one of the 75 said slips of each set when the other slip of the set is detached along the said weakened line for inclosing the folded-over end of the previously-used slip, and means for binding that end of one slip of each set opposite to the end adjacent the folded-over end of the set to corresponding ends of similar slips of the remaining sets to form a book.

4. In a manifolding book, the combination 85 of a plurality of sets of original and duplicate slips, each set formed from a single sheet of paper folded transversely intermediate of its ends and weakened along a line parallel to and adjacent to said line 90 of fold to provide a folded-over end at one end of one of the slips of the set when the other slip thereof is detached along the said weakened line, said folded-over end having a space designated on its upper surface 95 to receive notations of the amount to be forwarded or of the balance due.

5. In a manifolding book, the combination 100 of a plurality of superposed sets of slips, each set formed from a single sheet of paper folded transversely intermediate of its ends along a substantially unweakened line to form two slips, one longer than the other, the shorter slip being weakened along a line parallel to the line of fold to 105 provide an inseparable folded over-end when the said shorter slip is detached along said weakened line, means binding together the ends of the longer slips opposite to the ends connected with the shorter slips, and 110 a suitable transfer means between the slips of a set and extending only from the free end of the shorter slip substantially to the said weakened line.

6. The combination of a plurality of sets 115 of slips forming a pad, means for attaching one slip of each set to remain in the book, said slip having a suitably designated space to receive the balance due and to be forwarded, a back to which said sets of 120 slips are attached, a cover for the pad attached to said back and doubled back on itself along sets of transversely extending parallel lines to form a forwardly and downwardly inclined name-carrying section, 125 said cover being formed with a cutaway

portion to expose to view the said designated space, and a transfer medium arranged to be inserted between the slips of each set.

7. A manifolding book having a suitable back, a plurality of superposed sets of slips attached to said back, and a cover attached to said back and bent downward and forward and back upon itself to form a down-

ward forwardly inclined name-display section.

In testimony whereof I affix my signature, in presence of two witnesses.

BERT C. MAXWELL.
